UNITED STATES PATENT OFFICE

120,409

DESIGN FOR AN ASH TRAY

Eugene V. Myers, East Orange, N. J.

Application February 18, 1938, Serial No. 75,236

Term of patent 14 years

To all whom it may concern:

Be it known that I, Eugene V. Myers, a citizen of the United States of America, residing at East Orange, in the county of Essex, State of New Jersey, have invented a new, original, and ornamental Design for an Ash Tray, of which the following is a specification, reference being had to the accompanying drawing, forming a part thereof.

Fig. 1 is a perspective view of an ash tray showing my new design.

Fig. 2 is a section on the line 2—2 of Fig. 1.

The characteristic feature of the design resides in the ash tray having an enclosing wall and a plurality of concentric, spaced apart, upstanding ribs of substantial height, said ribs also being concentrically disposed in relation to the enclosing wall.

I claim:

The ornamental design for an ash tray, as shown and described.

EUGENE V. MYERS.
